UNITED STATES PATENT OFFICE.

CHARLES M. ZELL, OF THE DALLES, OREGON.

WASHING DEVICE FOR AUTOMOBILES AND OTHER PURPOSES.

Application filed December 8, 1922. Serial No. 605,671.

To all whom it may concern:

Be it known that I, CHARLES M. ZELL, a citizen of the United States of America, and resident of The Dalles, in the county 5 of Wasco, in the State of Oregon, have invented certain new and useful Washing Devices for Automobiles and Other Purposes, of which the following is a specification, reference being had to the accompanying drawing.

My invention relates to washing devices generally and has for its object the production of a flexible implement adapted for manipulation being preferably, for that 15 purpose, made in the form of a bag to fit loosely the hand of an operator, and being operatively connected with a water supply pipe in such form and manner as to distribute a flow of water from said pipe through 20 one side of the implement upon which is provided a soft detergent surface.

What constitutes my invention will be hereinafter described in detail and succinctly set forth in the appended claims.

25 In the drawing wherein my invention is illustrated in that form of embodiment which I at present prefer,

Figure I is a plan view of my device taken from that side thereof which carries a hand-stall.

Figure II is a longitudinal vertical section of my device taken as on the line II—II of Figure I.

Figure III is an end elevation of the 35 same looking from left to right.

Figure IV is a transverse vertical section of my device taken as on the line IV—IV of Figure II.

40 Referring to the numerals on the drawing, 1 and 2 (compare Figures II and IV) indicate two pieces of flexible, material preferably corresponding in shape and superficial dimensions, which are united face to face as illustrated, for example, in the figures of the drawing last named. The parts 1 and 2 are preferably made of canvas or sail cloth, heavy enough to hold water. They are united one to the other so as in effect to form a bag, as by a seam 45 of stitches 3 disposed at convenient distance from their common outside periphery. At one end of the said bag-like structure a pipe connection 4 is incorporated into the structure and made part of it. The 50 form of pipe connection illustrated is of familiar form and is presented by way of

example only of any suitable form that may be devised or preferred for the purpose. Within the bag defined by the seam 3 is provided an inside bag whose mouth 5 is located opposite the inner discharge end 6 of the connection 4 and in sufficiently close proximity thereto to enable it to receive discharge of liquid therefrom. I prefer to make said inside bag of the pieces 60 1 and 2 with no other addition thereto than that of means for defining one bag from the other. Such means preferably consists of an enclosing line of stitches 7 whose opposite ends 8 and 9 define the 65 mouth 5 aforesaid. The inside bag is preferably divided into two compartments as by a medial line of stitches 10 whose terminal 11 preferably divides, in effect, the mouth 5 into two.

Upon one side of the structure above described, I provide a series of apertures 14 and 15 which penetrate the fabric 1 or 2 on the one side and a cover-sheet 16 that is preferably incorporated into the 70 said structure. The cover-sheet 16 is preferably made of sheep skin with the wool out as indicated by the numeral 17, the wool, in such case, constituting a soft detergent surface for the device under 75 manipulation. The apertures 14 are distributed at suitable frequent intervals in communication with the outside or annular bag defined between the seams 3 and 7, while the apertures 15 communicate, in like 80 manner, with the interior of the inside bag whose outer periphery is defined by the seam 7.

The apertures 14 and 15 may be designated as palmar apertures because they are in use distributed through the walls of the implement over the palm of the hand of the operator who uses it. The cover-sheet 16 is preferably extended in a flap 18 well to the rear of the pipe connection 4 so as to interpose ample protection between said connection and a surface to be washed.

Upon the side of the device opposite the cover-sheet 16, I provide a backing 19, and at its forward end a strap piece 20 which is combined with said backing to constitute, in effect a pocket or hand-stall into which the hand of an operator may be thrust for the purpose of manipulating the device. 105 In practice, the parts 19 and 20 are, near 110 their outside edges, united together and to

the cover-sheet 16 by any suitable means, as for example a row of stitches, 21.

The operation of my device may, in view of the foregoing specification, be understood from the following brief description.

In use the pipe connection 4 is fastened to the end of a flexible hose, not illustrated, and from it a flow of water in sufficient volume and at desired pressure is delivered 10 through said connection into the interior of the outside and inside bags, respectively. Passing thence through the apertures 14 and 15 a constant supply of water is discharged through the woolly coating of the cover- 15 sheet 16 or similar material.

The flow of water operates, with detergent effect upon the said material itself as well as upon surface to be washed, so as to continually and quickly remove all grit or 20 abrasive material that may be present, with practical elimination thereof from injurious effect in the washing operation.

What I claim is:

1. A washing device of the class described 25 comprising a flexible bag having a liquid delivery opening in one end thereof, a central chamber formed in said bag, said chamber divided longitudinally into two com-

partments, a series of separate communicating compartments surrounding said 30 chamber, outlet openings in the bottom of said bag, and a hand engaging means secured to the top of the bag.

2. A washing device of the class described comprising a flexible bag having a liquid delivery opening in one end thereof, said bag being divided annularly along its outer margin into a series of separate communicating compartments and having a chamber formed within the central area of the bag, 40 said chamber being divided longitudinally into two compartments, outlet openings in the bottom of said bags, a pad secured to the underside of the bag and extending rearwardly beyond the liquid delivery opening, 45 a cover on the top of the bag, and a hand receiving pocket secured to said bag above the cover.

In testimony whereof, I have hereunto set my hand in the presence of two subscribing 50 witnesses.

CHARLES M. ZELL.
